TABULATING BOARD

Otto Blitz, Oakland, Calif.

Application April 26, 1935, Serial No. 18,360

7 Claims. (Cl. 129—16)

My invention relates to a tabulating board for use in accountancy, or the like arts, by means of which sales slips, or sheets of like nature, containing listed data, may be assembled with the corresponding data thereof in alined relationship to facilitate easy transference of the data, by an operator, to other records.

It is an object of my invention to provide a device of the character described which does not require the use therewith of specially perforated, or formed, data sheets.

Other objects of my invention are to provide a tabulating board in which the sheets are securely held in place to prevent accidental disarrangement thereof; to provide a tabulating board in which the securing means for holding the sheets operates to simultaneously clamp or release all of the sheets; to provide a tabulating board having an entirely level top surface unmarred by projecting pegs or other such sheet attachment means; to provide a tabulating board which permits instant reversal of the data sheets; and to provide a light-weight and sturdy board of the character described.

Additional objects and advantages of my invention will be apparent from a perusal of the following description forming a part of my specification.

Referring to the drawings:

Figure 1 is a plan view of a tabulating board incorporating the principles of my invention. The board is shown in its unlocked position.

Figure 2 is a plan view, similar to Figure 1, showing the board in its locked position with data sheets and reading straight-edge in position thereon.

Figure 3 is an enlarged perspective view of the clamp bars and their connecting links.

Figure 4 is a perspective view of a data sheet adapted for use with the tabulating board of my invention.

Figure 5 is a perspective view of the board showing how the data sheets are simultaneously reversed.

Figure 6 is a cross-sectional view of the board, drawn to an enlarged scale. The plane in which the view is taken is indicated by the line 6—6 of Figure 1.

Figure 7 is an enlarged plan view partly in section showing the locking means for the clamp bars.

In introduction, my invention comprises broadly, a frame having guides thereon in which is slidably mounted a plurality of bars each having a surface thereof alined with a surface of an

adjoining bar cooperating to provide a board having a level working surface. Means are provided connecting each of the bars together to permit limited relative movement therebetween whereby the bars may be moved into spaced relationship to provide a plurality of spaced slits into which sheets of material, such as paper, may be placed so that they are disposed on the board in overlapped, or shingled, relationship. Means are also provided for moving the bars into contiguous relationship, and locking them in this position, so that each sheet of material is clamped between the adjacent edges of adjoining bars.

In greater detail, the tabulating board of my invention comprises a rectangular frame having a pair of parallel side rails 2 and 3 joined together at their ends by cross members 4 and 6. The inner face of each side rail, as is best illustrated in Figure 6, is provided with a longitudinally extending groove 1 which serves as a guide, slidably engaged by the reduced ends 8 of a plurality of clamp bars 9 disposed transversely of the frame. The upper surface of each of these clamp bars is positioned in planar alinement with the surfaces of the bars adjoining it, and with the upper surfaces of the side rails and the cross members, so as to provide, as shown in Figure 2, a board having a level top surface.

Means are provided for moving the clamp bars into spaced relationship in the guides so as to form a series of spaced slits in the surface of the board between adjacent edges of each bar, and means are provided, connecting each of the bars, for limiting the spacing therebetween.

As is shown in Figure 3, the end 8 of each clamp bar is provided with a vertically disposed slot 11 which receives the inturned end 12 of a link 13 secured by means of screws 14 to the next adjoining clamp bar. The proportions of the link, the position of the slot, and the width thereof, of each bar, are such that, when the bars are spaced apart, a slit 16, of about one thirty-second of an inch in width, is formed between adjacent edges of the bars, and, when the edges of the bars are brought together into adjacent relationship, the slot 11 is of sufficient width to accommodate the movement of the end 12 of the link.

With the board in the condition shown in Figure 1, wherein the bars 9 are in spaced relationship, it will be seen that a sheet of material, such as the sales tag 17, having a marginal portion 18 and a main body portion 19 provided with data

spaces 21, may be placed in the board with the downwardly bent marginal portion, indicated by the dotted lines 22 of Figure 4, entering a slit 16 and the main body portion overlying the surface of the board as shown in Figure 2. When as many sheets as desired have been placed on the board the spaced clamp bars are moved in the guides to bring them into adjacent relationship in order to close the slits 16 and clamp the sheets therein.

Means are provided for moving the clamp bars and for locking them in adjacent relationship. Secured to the outer vertical face of the last clamp bar of the series, by means of screws 23, 15 is a rod 24 which extends through an aperture 26 formed in a bushing 27 which is secured in the cross member 4. The outer portion 28 of the rod is of reduced diameter upon which is rotatably mounted a sleeve 29 provided at one end 20 with a knurled handwheel 31 and at the other end with a screw thread 32 which engages mating threads 33 formed in the bushing. A screw 34 is threaded into the end of the rod 28 to prevent movement of the sleeve 29 beyond the end 25 thereof.

With the parts in the positions shown by the solid lines of Figure 7, the bars 9 are all in adjacent relationship, the screw thread 32 affording means for applying considerable pressure thereto 30 to clamp the data sheets against dislodgment from the slits. However, as soon as the handwheel 31 is rotated sufficiently to release the threads 32 from the bushing, so that the sleeve 29 may be moved outwardly, to the position 35 shown by the dotted line 36, the pressure is released, and the rod 24 is then free to be pulled by the operator through the aperture 26, thus moving the last clamp bar, above referred to, to a position adjacent the cross member 4 whereupon the other bars, due to their interconnection 40 with the last bar of the group, are also moved into spaced relationship one with the other.

In order to cover the space 37 between the cross member 4 and last clamp bar of the group, 45 a thin sheet metal apron 38 is provided with a downwardly directed flange 39 which may be attached to the bar 9 by suitable means, preferably by wood screws.

It is the usual practice in business houses such 50 as laundries or distributors of dairy products to provide their truck men with tags, similar to those illustrated in Figure 4, having the various items of stock listed thereon so that all that is required of the driver, upon making a delivery, 55 is to check the number of items disposed of on the tag and write in the address to which they were delivered. The filling in of the price and other data is often left to clerical help at the store as it has been found that this procedure greatly speeds up delivery and eliminates possible chances of error.

Thus it will be seen that each of the tags 17 positioned on the board in Figure 2 contains similar listed data and that when so positioned 65 it is a simple matter for a clerk to obtain sales totals therefrom for each of the listed items.

Guide means are provided to assist in reading the tags. Disposed longitudinally of the board 70 is a straight-edge 41 having an angle clip 42 secured to one end thereof which engages the outer vertical surface of the cross member 4, and a similar angle clip 43 secured to the opposite end thereof which is spaced from the outer vertical surface of the cross member 6. This latter 75 clip is provided with a boss 44 in which is

threaded a screw 46 provided with a winged head 47 and a plate at the inner end thereof which bears against the surface of the cross member. The screw 46 may be adjusted to regulate the pressure with which the clip 42 and the screw 5 plate engage the surfaces so as to provide sufficient friction therebetween so that the straight-edge may not be accidentally shifted, by shocks imparted to the board, once it is set, but may be freely moved by the operator transversely of the 10 board.

In some instances the tags 17 carry data on the reverse sides thereof which must be referred to in the course of tabulation. With reference to Figure 5, it will be seen that reversal of several 15 or all of the tags may be readily accomplished by removing the straight-edge from the board and raising the last tag at the right hand of the figure, whereupon by passing the hand along the surface of the board toward the left, each tag, 20 as it is lifted will assist in lifting several of the tags before it, with the result that, when the hand has reached the left hand end of the board, all of the tags will have been reversed. A reversal of this procedure will again restore the tags to 25 their former positions.

In reiteration, the tabulation board of my invention may be employed with any loose-leaf tag or data sheet; the sheets may not be readily displaced therefrom due to their being securely 30 clamped against such displacement; no specially prepared tags or sheets having perforations, or other means of attachment, are required for use with the board; and the tags may all be simultaneously clamped or released and readily re- 35 moved or replaced.

I claim:

1. A tabulating board comprising a plurality of parallel relatively movable members, means disposed between two of said members for limiting the degree of movement between it and an adjoining member to provide an opening therebetween into which objects may be placed, and means for clamping all of said members together to clamp said objects in said openings. 40

2. A tabulating board comprising a frame having a pair of parallel guides thereon, a plurality of parallelly disposed members engaging said guides and slidably movable longitudinally thereof, means secured to each of said members and engaging an adjoining member for limiting the degree of relative movement therebetween to provide an opening, between each pair of said members, of predetermined width into which objects may be placed, and means for clamping all 55 of said members together to close said openings to clamp said objects therein.

3. A tabulating board comprising a frame having a pair of parallel guides thereon, a plurality of parallelly disposed members engaging said 60 guides and slidably movable longitudinally thereof, means secured to each of said members and engaging an adjoining member for limiting the degree of relative movement therebetween to provide an opening, between each pair of said members, of predetermined width into which objects may be placed, means passing through said frame and secured to one of said members for moving said members in said guides, and means for locking said moving means to said frame. 65

4. A tabulating board comprising a frame having a pair of parallel guides thereon, a plurality of parallelly disposed members engaging said guides and slidably movable longitudinally thereof, means secured to each of said members 70

and engaging an adjoining member for limiting the degree of relative movement therebetween to provide an opening, between each pair of said members, of predetermined width into which objects may be placed, said means comprising a link secured to each of said members and movable relatively with an adjoining member into engagement therewith, and means for clamping all of said members together to close said openings to clamp said objects therein.

5. A tabulating board comprising a frame having a pair of parallel guides thereon, a plurality of parallelly disposed members engaging said guides and slidably movable longitudinally thereof, each of said members having a vertically disposed notch therein, a link secured to each of said members and having a portion thereof entering said notch for limiting the degree of relative movement between said members to provide therebetween an opening of predetermined width into which objects may be placed, and means for clamping all of said members together to close said openings to clamp said objects therein.

10 15 20 25 6. A tabulating board comprising a rectangular

frame having a pair of parallel guides thereon, a plurality of parallelly disposed members engaging said guides and slidably movable longitudinally of said frame, said members being movable from spaced positions adjacent one end of said frame to contiguous positions adjacent the other end of said frame so as to provide an open space between one of said members and a portion of said frame, and a plate secured to one of said members and disposed in parallel relationship with said frame for closing said open space.

7. A tabulating board comprising a rectangular frame having a pair of parallel guides thereon, a plurality of parallelly disposed members engaging said guides and slidably movable from mutually contiguous positions adjacent one end of said frame so as to provide a space between one of said members and said frame, to spaced positions in said frame so as to provide a plurality of spaces therebetween, and a plate secured to one of said members and movable therewith, said plate closing said space between one of said members and said frame when said members are in contiguous relationship.
